UNITED STATES PATENT OFFICE.

JOHN E. LORD, OF OAK PARK, ILLINOIS, ASSIGNOR OF ONE-HALF TO WILLIAM A. SPICKERMAN, OF OAK PARK, ILLINOIS.

PACKAGE-TIE.

1,176,382.

Specification of Letters Patent. Patented Mar. 21, 1916.

Application filed October 12, 1914. Serial No. 866,280.

To all whom it may concern:

Be it known that I, JOHN E. LORD, a citizen of the United States, residing at Oak Park, in the county of Cook and State of Illinois, have invented a new and useful Improvement in Package-Ties, of which the following is a specification.

My invention relates particularly to a package-tie of such a character that a tie can be readily effected and also readily undone, the device being capable of repeated use.

My primary object is to provide a device of the character indicated which is of exceedingly simple and cheap construction, which will operate to insure a thoroughly secure engagement between the cord and cord-securing member without preventing disengagement by facile manipulation, and which, by reason of the principle employed, is exceedingly durable, or long-lived, thus enabling the device to be used over and over again, indefinitely. Such a device is well adapted for tying packages of various kinds; and it is especially desirable for mail service, where it can be used by post office clerks, railway and mail clerks, and letter carriers for temporarily securing together letters, and other small mail packages.

The invention is illustrated in its preferred embodiment in the accompanying drawing, in which—

Figure 1 shows a perspective view of a package with my improved package-tie applied thereto; Fig. 2, a broken vertical sectional view illustrating the position which the cord assumes in the first portion of the securing operation; and Fig. 3 represents a similar section illustrating the manner in which the cord is wedged or secured within the upwardly converging walls of the central portion of the cord-securing device, or button.

In the illustration given, A represents a package; and B a package-tie applied thereto. The device B preferably comprises a cord 1 and a cord-securing device 2. The device 2 is preferably formed from a disk of sheet-metal which has an upwardly struck hollow conical central portion 3 of contracted area, the lower or widened portion merging with and being encircled by a substantially flat disk portion 4, which has its outer edge curved upwardly and in-

wardly to form a circumferential bead 5. The lower and inner surface of the device, as well as the circumferential bead are preferably made perfectly smooth to facilitate the tying and untying operation and prevent abrasion of the cord. The preferred manner of securing one end of the cord to the member 2 is to provide the apex of the cone 3 with a perforation through which one end of the cord is passed from below, the cord then being knotted above the apex, as indicated at 6. To prevent abrasion of the cord, the metal is struck downwardly at the small opening and wedged close against the inner wall of the cone at the apex thereof, leaving only a smooth portion to come in contact with the cord.

In the illustration given, the cord is shown as forming a loop about the package with the portions 1^a and 1^b lying on the upper surface of the package. In effecting a tie, the free end 1^c of the cord is passed about the attached end of the cord and beneath the button 2, the cord being drawn quite taut, thus forcing the loop 1^c to assume a position well up within the apex of the cone, as illustrated in Fig. 2. The free end of the cord is then carried again around the attached end and beneath the button, forming a second convolution 1^d, which, by reason of the peculiar formation of the button, naturally assumes a position beneath the first convolution; and as the cord is drawn taut, the second convolution forces the first convolution snugly up between the converging walls at the upper end of the cone, while the second convolution is itself wedged between the converging walls of the cone and is firmly bound against the walls of the cone by the portions 1^a and 1^b of the cord, as I have endeavored to illustrate in Fig. 3.

It will now be understood that the cord is firmly secured by the wedging action within the small hollow conical portion of the button. The result is that the tie cannot become loosened by lifting the button and cord away from the package, or by turning the button upon its axis in either direction. Moreover, it will be seen that the tying operation can be effected in a very facile manner, and that the tie can be equally released in a facile manner. Moreover, there are no serrations or teeth em-

ployed on the device, and there is nothing to injure or abrade the cord or hurt the hands of the user.

It is preferred to have the cord fit snugly 5 within the central perforation, but in a manner to enable the cord to be withdrawn and replaced by a new cord, if desired. There is no objection to the button being 10 free to turn on its axis, since such a movement will not effect the loosening of the cord when wrapped or secured in the manner described.

The button may be formed of any suitable material, and no unnecessary limitation 15 should be understood from the foregoing detailed description.

What I regard as new, and desire to secure by Letters Patent, is—

1. A package-fastener, comprising a cord- 20 securing member having a central portion provided with upwardly convergent walls with a contracted area between them and having a continuous smooth peripheral portion provided with an upwardly curved edge 25 surface beneath which the cord may be freely passed in effecting a tie, and a cord having one end secured to the central portion of the device, said cord depending through said central portion and said central portion being adapted to hold the convolutions of the cord by a wedging action, 30 for the purpose set forth.

2. A package-fastener, comprising a cord-

securing member of general disk form having a hollow central portion provided with upwardly convergent walls affording between them a contracted area, said member having a curved circumferential edge wall and a continuous smooth under and inner surface, and a cord having one end portion secured to the central apex portion of said member and depending through said central portion, whereby the convolutions of the cord will be forced into and secured within said central portion when the free end of the cord is wrapped about the attached portion beneath said securing member. 35

3. A package-fastener, comprising a circular member having an upwardly struck conical central portion bounded by a peripheral portion having an upwardly and inwardly curved flange, the outer edge portion and under surface of said member being continuous and smooth, and a cord having one end portion secured to the central apex portion of said member and depending through the hollow conical central portion, whereby the convolutions of the cord will be forced into and securely held within said conical central portion when the free end of the cord is wrapped about the attached end beneath the disk. 40

JOHN E. LORD.
